UNITED STATES PATENT OFFICE.

CHARLES EDGAR WICKERSHAM, OF MOUNT VERNON, ILLINOIS, ASSIGNOR OF ONE-HALF TO B. E. WILLIS, OF MOUNT VERNON, ILLINOIS.

DROP-DOOR MECHANISM.

Specification of Letters Patent. Patented Sept. 7, 1915.

1,153,146.

Application filed January 5, 1914. Serial No. 810,334.

To all whom it may concern:

Be it known that I, CHARLES E. WICKERSHAM, a citizen of the United States, and a resident of Mount Vernon, in the county of Jefferson and State of Illinois, have invented a new and Improved Drop-Door Mechanism, of which the following is a full, clear, and exact description.

My invention is designed for embodiment in gondola cars and the like and relates particularly to a drop-door mechanism so constructed and arranged as to provide for either a side discharge or a center discharge of the load, as may be desired.

In carrying out the invention hinge butts are provided at each end of the door and specifically in the preferred form, the hinges comprise drop members, either of which may be released to permit the door to swing on the opposite hinges, the doors in practice being arranged on each side of the car to operate in groups of two or three doors to each end of the car. In connection with the doors of the character indicated, supports or rests are provided for sustaining the doors, the rests being arranged to be moved from a central position, sustaining the doors in the closed position, laterally in the direction of either side of the car according to the direction in which the door is to swing for a center or side discharge of the load. The door rests are caused to move in a straight line beneath the door, being caused to advance or recede in suitable guides, to or from the central position to permit the door to gravitate to a lowered position or to raise the door to a closed position.

The distinguishing features of my invention and the improved structural elements characterizing the practical embodiment, which is illustrated as an example, will be more particularly explained in the specific description hereinafter to be given.

Reference is to be had to the accompanying drawings forming a part of this specification in which similar characters of reference indicate corresponding parts in all the views, and in which—

Figure 1 is a partial sectional plan view of a gondola car provided with my improved drop-door mechanism; Fig. 2 is a longitudinal vertical section on line 2—2 of Fig. 1; Figs. 3, 4 and 5 are transverse sections taken respectively on the lines 3—3, 4—4 and 5—5

of Fig. 2; Fig. 6 is a detail side elevation of one of the hinges; and Fig. 7 is a front view of said hinge.

In the drawings there is shown more or less conventionally, a center sill 10, a side sill 11, an end sill 12 and cross ties or cross bearers 13—13^a. I have shown one drop-door 14, which is to be arranged in the car bottom 15. It is to be understood that any approved number and arrangement of the doors may be adopted, as for instance, the usual equipment for a general service car.

The door 14 is supported at each side by hinges, composed of fixed upper butts or hinge members 16, suitably riveted or otherwise secured to the center sill and side sill respectively, and lower drop-hinge butts 17, the door being provided at each side with hinge pintles 18, which may be formed on brackets 19, secured to the under side of the door. The hinge butts are provided with concave bearings 16^a—17^a, which accommodate the hinge pintles 18.

The sills 10, 11, are in the form of U-beams with the flanges of the former disposed outwardly and the flanges of the side sills disposed inwardly toward the center sill. The upper hinge members 16 are generally of angular form and present vertical members and top members at an angle corresponding to and received in the upper entrant angles of the U-beam sills 10, 11. By thus forming the hinge elements 16, and securing them in the upper entrant angle of the U-beams, the latter form a backing for said hinge elements both at the back and at the top to adapt the hinge elements to rigidly resist the up-thrust of the pintles 18 of the doors when the latter are swung on their hinges. To raise and lower the hinge butts, 17, I provide suitable means to rock the same to or from the mating hinge butts 16. The hinge butts 17 are mounted on rock shafts 20 ranging lengthwise of the side sills 11 and located between the upper and lower flanges of said sills at the inner side thereof. The shafts turn in suitable bearings in the cross-bearers 13, 13^a and in bearing lugs 16^b on the fixed hinge elements 16. Thus each hinge element 16 presents a bearing for a rock shaft 20 carrying the mating hinge elements 17 and forms a thrust bearing for the hinge pintles 18 of the door. By thus supporting and positioning the rock shafts 20 those on the side sills 11 will be at

105
110

the inner sides of the sill so that neither the 5 hinges nor their operating means will present any projections at the exterior of the sides of the car. The shafts 20 are rocked in any suitable manner, as for instance, by providing a ratchet wheel 21 on each shaft to be engaged by a pawl 22, which may be mounted on a lever 23 hung on each shaft, as shown at the left of Fig. 2, the pawl and ratchet thus serving to hold the shaft against turning, for sustaining the door in a raised position.

Associated with the described door and its 10 hinges, I provide means constituting a rest for the door and a means for raising the door after having been dropped, it being understood that the means will be extended under a plurality of doors in practice. Thus to the end mentioned, rollers 24 are provided 15 on a shaft 25, which ranges lengthwise of the car and has guided movement and support in slots 26, formed in the cross bearers 13-13^a. The doors 14 are provided with ribs 14^a, having a horizontal central portion 20 14^b, and beveled or upwardly inclined ends 14^c, constituting inclined planes.

The shaft 25 is arranged to be moved in a straight line in the guide slots 26, or equivalent guide means, to cause the rollers 24 to recede from the central position shown in Fig. 5, full lines, toward either side of the car, as for instance as indicated in dotted lines at the left of the figure. To actuate the shaft 25, there is shown in the present example, a worm wheel 27 on one end of said shaft meshing with a worm shaft 28, provided with suitable means for turning same.

The turning means for the worm shaft 40 28 may consist, as shown in Figs. 1 and 3, of a ratchet wheel 31 on the shaft, which is engaged by a pawl 30 on a handled rock lever 29. To give the parallel movement to the shaft 25 in response to the turning of the worm wheel 27, spur pinions 32 are secured to the shaft at the cross bearers 13 and these spur pinions mesh with rack bars 33, which may be secured to the said cross bearers, preferably above the guide slots 26 45 in which the shaft 25 travels.

To afford a proper track for the shaft, an angle track 34 is provided at the bottom of each slot 26 and the spur pinions 32 have hubs or bosses 32^a that travel on the horizontal member of the said angle tracks.

With the described construction, it will be obvious that the drop elements 17 of the hinges at either end may be lowered by turning of the respective shaft 20, which will 55 release the adjacent end of the door 14 and cause said door to gravitate downwardly and swing on the opposite hinge pintle 18, as indicated in Fig. 5. To permit the door to drop after the release of the drop hinge member, the door supporting rollers 24 and

their shaft 25 are moved transversely of the car in the direction of the hinged end of the door, by turning the worm shaft 28. To close the door, a reverse movement is given to the worm wheel 28, which will advance the shaft 25 and the rollers 24, along the adjacent inclined planes 14^c of the ribs 14^a, or equivalent elements on the door, thus causing the door to rise to the closed position, the rollers 24 finally taking positions beneath the horizontal central portions 14^b of the ribs 14^a.

It is to be noted that the shaft 25 and its rollers 24, may be shifted laterally to any desired extent to permit the doors to drop to a greater or less degree, thereby varying the extent of the discharge opening at either side, and the door will be firmly supported in the given position. The regulating of the discharge opening is especially desirable in the case of ballast cars.

It will be observed that the hinges are protected against the formation of an ice seal in cold weather, the inner hinges adjacent the center sill being located beneath the adjacent portions of the floor 15, (see Fig. 5) while those hinges at the side sill 11 are protected by a cover element 35, which may be in the form of an angular flange on the floor 15. It will be seen that the hinged edges of the door extend beneath the floor at the door opening 14^a and the hinges and door edges are thus well protected against the formation of an ice seal and upon releasing either side edge of the door, it will be free to swing, the weight serving to break any partial ice seal that may be formed between the door and adjacent portions of the floor.

It will be obvious that the worm 28 and worm wheel 27 constitute a lock to maintain the shaft 25 in a given position, since the worm wheel cannot turn the worm.

By the described construction, I provide in a simple manner, for an efficient side discharge or center discharge of the load, as may be desired.

The described construction affords a practical means for carrying my invention into effect, and I would state in conclusion that I do not limit myself strictly to the mechanical details herein illustrated, since manifestly the same can be considerably varied without departure from the spirit of the invention.

Having thus described my invention, I claim as new and desire to secure by Letters Patent:-

1. In a car, a drop-door presenting opposite inclined planes, hinge means at opposite edges of the door, and door supporting means movable over the door into contact with either of the inclined planes.

2. In a car, a drop-door presenting opposite inclined planes and an intermediate

surface therebetween, hinge means at opposite edges of the door and door supporting means movable over the door from the said intermediate surface into contact with either 5 of the inclined planes.

3. In a car, a drop-door, means at opposite side edges to optionally hinge the door at either of said edges, a door support including a shaft ranging beneath the door, 10 a track on which the shaft may travel transversely, a worm wheel on said shaft, and a worm meshing with the worm wheel.

4. In a car, sills in the form of U-beams the flanges of one sill being disposed toward 15 the flanges of the opposite sill, and a drop door between the sills, said door having hinge pintles thereon at opposite side edges, hinge elements at the opposite edges of the door fixedly secured to the sills, said hinge 20 elements presenting vertical and top members conforming with the upper entrant angles of the U-beams and fitting in said angles, the upper flanges of the beams overlying and forming a backing for the top 25 members of the said hinge elements and the webs of the beams forming a backing for the vertical members of said hinge elements, rock shafts having bearings on the vertical members of said fixed hinge elements, and 30 co-acting hinge elements on said rock shafts

below and adjacent to the fixed hinge elements, said fixed hinge elements and said co-acting hinge elements having corresponding bearing depressions jointly receiving the hinge pintles on the door, the said 35 pintles at either side being releasable by a rocking of the adjacent shaft to drop the hinge elements thereof.

5. In a car, side sills and center sills in the 40 form of U-beams, the flanges of one sill being disposed toward the flanges of the opposite sill, drop doors between the sills, said doors having hinge pintles at opposite side edges, rock shafts ranging lengthwise of the sills between the flanges thereof, hinge 45 elements on the shafts to rock therewith, and hinge elements of angular form fixedly secured to the U-beams in the upper entrant angles thereof, above the first mentioned hinge elements, both of said hinge elements 50 having mating depressions accommodating the hinge pintles on the doors.

In testimony whereof I have signed my name to this specification in the presence of two subscribing witnesses.

CHARLES EDGAR WICKERSHAM.
